UNITED STATES PATENT OFFICE.

LEROY D. KELLOGG, OF CHICAGO, ILLINOIS, ASSIGNOR, BY MESNE ASSIGNMENTS, TO
KELLOGG SWITCHBOARD & SUPPLY COMPANY, A CORPORATION OF ILLINOIS.

TELEPHONE-EXCHANGE SYSTEM.

1,204,783.

Specification of Letters Patent. Patented Nov. 14, 1916.

Application filed November 27, 1906. Serial No. 345,290.

To all whom it may concern:

Be it known that I, LEROY D. KELLOGG, a citizen of the United States, residing at Chicago, in the county of Cook and State of Illinois, have invented new and useful Improvements in Telephone-Exchange Systems, of which the following is a specification.

My invention relates to telephone systems wherein trunk or link-circuits are employed, adapted to be used for putting through the connections of a plurality of telephone circuits by the aid of electrically controlled or adjusted selective switching mechanisms associated with said links, an object of my invention being to provide a structure wherein the said switching mechanism of a link or trunk may be indifferently employed for incoming and outgoing calls of the telephone circuits which the trunk may serve.

A feature of the invention consists in this that the same selective switch may be employed to extend a circuit served by it to a desired point, or may be employed to extend connection from another point to a circuit served by it.

I have elected to show my invention applied to a system wherein a plurality of selective switches common to a plurality of lines, are employed to automatically connect the central office link-circuits operatively with calling lines and wherein the same switches are employed, to automatically extend the circuit of the calling line to the called line.

In accordance with the application of my invention herein shown, I provide a number of switches common to a group of lines and so arrange their circuits and mechanism that each one may be employed for either of the above indicated purposes; that is to say, for a group of one hundred lines, for instance, ten such switches may be provided and each one is indifferently available, until placed in use and so rendered busy, for outgoing or incoming calls of the lines of the group. I am aware that it has heretofore been proposed to employ switches common to a plurality of circuits for automatically connecting a link-circuit to a calling circuit over which link-circuit the connection may be completed, and that systems have also been proposed wherein selective

switches were to be employed to connect with called circuits, and that systems have been proposed including both of the above characteristics. I am, however, not aware of any prior system wherein a selective switch is provided capable of use in either direction or capacity interchangeable.

Referring to the drawings Figures 1 and 2, illustrate diagrammatically circuits of a telephone system embodying an application of my invention. Figs. 3 and 4 show respectively top and side views of a master-switch. Figs. 5 and 6 are similar views of a selective switch employed in connections with the circuits.

In accordance with the embodiment of my invention shown, I provide for a group of lines, say fifty or one hundred, a number of selective switches proportioned in number to the number of co-existing calls to be expected from and to the lines of the group at the busiest time. These switches serve the lines (as calling lines) to automatically connect to them circuits over which the connections may be completed. They are preferably not constantly operating devices, but remain at rest until a signal is sent over a calling line, whereupon a distributing device causes an idle switch to start its operation which then automatically continues until the switch has sought out and found a calling line. Conversely the switches serve the lines of the group to which they are assigned, as called lines, to complete circuits from lines of the same or other groups to them as such called lines. It is, of course, essential in such an arrangement that as soon as a switch is put in use for either purpose it be rendered unavailable for other use in either capacity until released at the proper time, and to that end, I arrange the structure so that a busy potential or indication is placed upon all circuits of a busy switch by which it may in its normal condition be influenced.

It is obvious that my invention will render any system to which may be applied, extremely flexible in character inasmuch as a fixed percentage of switches assigned to any group of circuits will enable a number of outgoing calls totaling the number of switches to co-exist from the group or the same number of incoming calls may co-exist; or the number of outgoing and incom-

2
ing calls may be in any proportion, limited only by the number of switches.

It is not my intention to limit the claims in such manner that they will not cover my invention in connection with purely automatic telephone systems, in which it may obviously be employed, although the particular application I herein show includes a system in which certain portions of the connections are completed by the aid of central office operators.

In Figs. 1 and 2, I show an application of my invention to the supplying of service resembling to a certain extent lockout party line service. In the system therein shown each of a group of, say, fifty subscribers has his individual substation and a short line extending therefrom to a location wherein are placed a plurality of selective switches, say five or ten. Each line may there terminate in passive multiple contacts appearing in the banks and being adapted to be engaged by each of said switches. Assuming five switches to be provided, five trunk lines, each individual to a switch would be provided extending to a central office where they may terminate in an answering jack, with an associated signal, and multiple jacks. A subscriber making a call will by the removal of his receiver alter the electrical condition of his individual short line to cause a switch to connect his trunk line to the short line; the exchange signal of that trunk line will be displayed and the operator will answer as in usual manual practice by inserting an answering plug in the answering jack associated with the signal, learn the number wanted and complete the connection by inserting the calling plug belonging to the answering plug used, after making the usual busy test, into a multiple spring jack having connections suitable for completing the call. This multiple spring jack may be a terminal individual to a subscriber's line or it may be a terminal pertaining to a trunk line leading to a selective switch of the character hereinbefore described, belonging to the same group of lines among which the calling line is included or belonging to another similar group. In case such trunk or link-circuit is used, the operator will employ her calling device, of which one may be provided per position with keys for connecting it to any cord at the position, to transmit directive currents to the trunk switch to adjust it to connection with the particular line wanted, when the switch will automatically test the called line and if the same be found busy, the switch will be automatically restored to normal and a busy signal extended to the calling subscriber or operator. I provide the usual supervisory signaling apparatus, one signal being controlled by each subscriber and preferably organize the system

in such manner that after connection has once been completed between two lines, the restoration of the selective switch is solely controlled by the operator.

My invention will be more particularly described in connection with the accompanying drawings, but it will be understood that the invention is not limited to the particular application and instrumentalities in association with which I have elected to illustrate and describe it.

Generally stated, an exchange organized to employ the arrangements shown in Figs. 1 and 2 may comprise a group or a plurality of groups of lines such as that of A, each group having its master-switch K, one for the group, and a plurality of selective switches C common to the group. The switches of a group are preferably placed at a location as close as possible to the substations in order that the individual lines L, L' may be as short as possible while the trunk lines L, L', in number only a small percentage of the individual lines, form the long links giving access to the exchange. The multiple spring jacks of the trunks may appear at each section of the usual multiple switchboard along with the multiple jacks of ordinary subscribers' lines such as that of E. The multiple trunk jacks of a group of switches are preferably mounted in the multiple jack frame adjacent to one another in order that an operator making the usual test to find an idle trunk of the group may have them all close together. The call lamps and answering jacks of the trunks belonging to a particular group of subscribers may all be placed at one operator's position or may be distributed among several operators.

Referring more specifically to Figs. 1 and 2, as shown at A, a subscriber's substation equipment includes the usual transmitter, receiver, condenser and bell with hook lever 1 normally closing the bell circuit, and adapted, on removal of the receiver, to open said circuit and connect the transmitter and receiver operatively with the line. The said line is provided at the exchange with the line relay 2, adapted, when a call is initiated at the substation, to operate the master-switch mechanism K to start an idle selective switch C in search of the calling line. The line is also provided with multiple contacts 14-16-18-20 appearing with those of other lines of the group among which that of A is included, which may number fifty, in the banks of each of the selective switches of which there may be five. The line relay 2 when operated also removes ground from the multiple contacts 18 to render the line selectable by the instrumentality of the private wiper 19 of the started switch C which controls its operation. The circuits of said switch extend by the limbs L and L' of a trunk line to the central office, being there

provided with signal relay 47 with its associated lamp 50 and cut-off relay 46 and the associated multiple spring jacks. As soon as switch C is started, signal lamp 50 is displayed and a busy test placed upon the test contacts 51 of the multiple jacks. The operator answers the call by inserting the answering plug G of her cord circuit E into the answering spring jack directly associated with the signal lamp, it being understood, that the multiples of said spring jack appear at the various sections of the multiple switchboard in the usual manner. The operator will then inquire the number of the subscriber wanted, and if the line wanted be an individual line such as that of F, the operator will, after testing the line, insert the calling plug H of the cord circuit E into a multiple jack of the wanted line and rings the called subscriber in the usual manner. The replacing by the two connected subscribers of their receivers at the conclusion of conversation will display the supervisory signal lamps 64 and 88, and the operator will withdraw the two plugs of the cord circuit, the withdrawal of the answering plug causing the switch C to return to normal and be available for further calls. Assuming however, that the line wanted is a line included in the same group as that of A or any other similar group, the operator in such case, by means of the calling plug of the cord circuit, will test the multiple spring jacks of the trunks pertaining to the group among which the line of the called subscriber is included, and on finding an idle jack will insert the calling plug therein, which act will place a busy potential on the test contacts 51; the operator will then actuate the impulse transmitter 74 to send a number of impulses representing the number of the called subscriber in his group. The transmission of the first impulse in addition to advancing the selected switch C a step toward the called line, removes said switch from all control exercised by the master switch mechanism K. When the proper number of impulses have been transmitted by calling device 74 to place wipers 15-17-19-21 upon contacts of the called line, the said line will be automatically tested by the switch C. If the said line be found busy, the selector will be automatically restored to normal and the operator will receive a busy signal in her telephone, and will take down the connection in the usual manner. If the line be found idle, no busy signal will be received and the switch will, of course, remain in connection with the contacts of the called line, the operator then including the generator in circuit with the called line to ring the bell of the called subscriber. The cord circuit arrangement shown at E is adapted for use in completing connection between two lines of the character of that shown at A, or

two lines the character of that shown at F, or between two lines of the different classes of which either one may be the calling line.

To trace more in detail the operation of the mechanism described, let it be assumed that the subscriber at A desires his line to be connected with that of the subscriber at F. He removes his receiver from the hook lever causing the energization of relay 2 by current from battery B, through the said relay, normal contact of armature 4, over line limb L², hook lever 1, returning over line limb L¹ and back contact of upper armature of relay 3 to ground. Relay 2 in attracting its upper armature closes a locking circuit for itself to ground at the upper armature of relay 3. The lower armature of relay 2 is attracted to remove the normal ground from the multiple contacts 18 of the line, and by engaging contact 2^a to close circuit through relay 6 of the master switch mechanism K, energizing the said relay, which in attracting its armature, completes a circuit from ground through the back contact of the armature of relay 9, contacts 10-12; (it being assumed that the master switch wipers 10-11 are engaging the contacts 12-13 pertaining to switch C) over conductor 56, normal contact of armature 31, back contact of armature of relay 42 through relay 22 to battery. The said relay 22 attracts its armatures of which 23 and 28 place line wipers 15-17 upon open circuit in order that they may not interfere with conversations existing over lines whose contacts they may wipe in the operation of the switch C. Armature 27 completes a circuit from ground through relay 38 over limb L¹ of the trunk circuit to the exchange, through relay 47 thereat to battery B', operating relay 38 to disconnect polarized test relay 39 from the alternate contact of armature 28 in order that said relay 39 may not be connected to line wiper 17 while it is wiping over busy contacts. The energized relay 47 attracts the armature 49 to display lamp 50 and armature 48 to connect battery to the test contacts 51 of the trunk spring jacks to render them busy. Thus, as soon as switch C has its starting relay 22 operated as a line selector, the trunk jacks are rendered busy. In other words, the change in the normal electrical condition of the non-multiple terminal 12, corresponding to the link-circuit, renders busy the multiple jack terminals. The attraction of armature 24 of relay 22 completes a circuit from ground through back contact of armature 30 through operating magnet M, back contact of armature 33 and through interrupter I to battery B, while armature 25 connects the winding of relay 22 with the private wiper 19. The interrupter I now transmits current impulses through magnet M, each actuation of said magnet advancing the

wipers a step until the relay 22 becomes deenergized, when the retraction of its armature 24 will prevent further operation of magnet M. For purposes hereinafter more fully explained, the first contact engaged by a wiper 19, when a switch has started to operate, is permanently connected to ground, while the first contacts engaged by the other wipers 15-17-21, are open or dead contacts. When with the first actuation of the magnet M, wiper 19 engages the grounded contact, a locking circuit is completed from battery B through relay 22, back contact of armature of relay 42, armature 25 and its alternate contact, wiper 19 to ground, holding relay 22 energized. Magnet M now advances the wipers 15-17-19-21 step-by-step over the sets of multiple contacts 14-16-18-20 of the different lines, the contacts 18 of such lines as are not calling lines, being grounded at the normal contacts of the lower armatures of the line relays 2. Thus, successive locking circuits are established for relay 22 holding it energized, but as soon as wiper 19 engages a contact 18 of the calling line, that of A, said contact is then ungrounded because relay 2 of that line is operated, circuit through relay 22 is opened and all its armatures retracted, armatures 23 and 28 closing the circuits of the talking conductors of the trunk circuit, while armature 24 prevents further operation of magnet M, leaving wipers 15-17-19-21 engaging respectively contacts 14-16-18-20 of the calling line, and armature 27 allows relay 38 to be deenergized. Relay 22 thus acts as a test relay in establishing connection with line L²-L³ as a calling line.

With the first actuation of magnet M, the off-normal switch springs O.N', O.N², O.N³, O.N⁴ and O.N⁵ were simultaneously shifted to their alternate positions, the shifting of O.N' completing circuit from ground through conductor 57, contact 13, wiper 11 of the master-switch, relay 7 to battery. The relay 7 attracts its armature, completing circuit through magnet 8 which, owing to the interrupter controlled by its armature, is successively energized and deenergized as long as relay 7 holds its armature attracted, stepping wipers 10-11 over contacts 12-13 of the different switches C. Relay 7 continues energized until wiper 11 reaches a contact 13 of a switch C which is at normal, as it then for the first time fails to find an ungrounded conductor 57 since the contacts O.N' of all busy switches are shifted. When wipers 10-11 do reach contacts 12-13 of an idle switch, relay 7 becomes deenergized preventing further operation of magnet 8 and the wipers remain in engaging the contacts of the said idle switch.

As soon as relay 22 is deenergized, circuit is completed from battery B' through relay 47, back contact of armature of relay 46, through relay 34, back contact of armature 28, contact 17-16, cut-off relay 3 to ground, energizing the said cut-off relay 70 whose attracted armatures extend limbs L² and L³ to the trunk conductors, and open the circuit through line relay 2 whose armatures now fall back, the lower armature causing relay 6 to become deenergized unless another substation of the group has its receiver removed by a calling subscriber, when contact 2' or 2² will be grounded by the operation of the respective line relay 2. The retraction of the lower armature of relay 2 also places ground upon multiple contact 18 of the line rendering it again unselectable by any switch C operating as a line selector. It will be observed that relay 6, after relay 2 has once operated, continues energized as long as the said relay 2 does, while wipers 10-11 start to seek contacts 12-13 of an idle switch C as soon as the one started has closed its contact O.N'. To prevent an untoward starting of this other line selector, I provide the relay 9 connected from battery to conductor 58 having taps ending in contacts 45-45'-45'', etc., one for each relay 22 of the different switches C. Thus, as long as any relay 22 continues energized, a circuit will be closed from ground through its armature 26 to contact 45 45', etc., through relay 9 to battery, which relay by attracting its armature, holds the starting circuit of wiper 10 open as long as a switch C is in operation. Thus a second switch cannot be started by master-switch K as long as one switch C is in operation. It will be remembered that relay 22 allows its armatures to fall back to cause the energization of relay 3 which deenergizes in turn relays 2 and 6. Inasmuch as current may be interrupted through relay 9 at contact 45 a fraction of a second before current is interrupted through relay 6, the relay 9 is preferably so constructed as to release its armature slowly after current is interrupted therethrough to insure the deenergization of relay 6 before the armature of relay 9 closes its back contact. Of course, if another subscriber has removed his receiver as a calling subscriber, relay 6 will be held operated, and upon the retraction of the armature of relay 9, a second switch C will be started as a line selector. A copper shell may be placed about the core of relay 9 to render the release of its armature sluggish.

The operation of relay 34 takes place simultaneously with that of relay 3, and the attraction of its left-hand armature completes a circuit from ground through relay 29 to battery, which relay is immediately locked by current passing from ground through the shifted off-normal spring O.N³, attracted armature 32, relay 29 to battery.

The attraction of armature 35 opens a circuit of relay 37, while armature 36 closes a normally open contact in the circuit of release magnet RM; but as armature 5 of relay 3 is attracted, RM is not energized. When the operator answers the call by inserting the answering plug G of her cord circuit E into the answering jack of the trunk line whose signal 50 is displayed, contacts 59 and 60 engage springs 53 and 54 respectively, while contact 61 crosses thimbles 51 and 52. The plugs of the cord circuit are preferably so constructed that when being inserted into a springjack such as that shown at D, the contacts 60 and 81 do not engage the thimbles 52 and 51, in order that the cut-off relay 46 may not be operated before battery has been applied to spring 54. This may be effected by making contacts 60 and 81 slightly smaller, as shown, than the bushings of insulating material on each side of them. It is immaterial whether the operator inserts the plug before or after the calling line has been selected. Upon the insertion of the plug G in the answering jack at D, circuit is completed from battery B² through contact 61-52, relay 46 to ground, energizing relay 46 which attracts its armature to engage its alternate contact. Relay 47 is thereby deenergized and lamp 50 goes out. Current then flows from battery B² through relay 63, contact 60-54, armature of relay 46, limb L', relay 34, armature 28, contact 17-16, relay 3 to ground, a portion also flowing over limb L², hook lever 1, limb L³, contact 14-15, armature 23, limb L, contact 53-59, relay 62 to ground. Relay 62 is energized and attracts its armature to prevent the display of signal 64 at this time. The shifting of current through relays 34 and 3 at the armature of relay 46 occurring on the insertion of the answering plug, is accomplished quickly so that relays 34 and 3, if already energized by the selection of the calling line before insertion of the answering plug, hold their armatures attracted.

The operator now depresses levers 69 and 70 of her listening key, learns the number of the subscriber wanted, assumed to be F, and touches tip 80 of the calling plug to sleeve 83 of a multiple jack of the line of F. If the line is busy, contact 83 will be of a potential other than ground, and current will flow through tip 80, levers 77-71, armature 67, test relay 68 to ground, and the relay will be energized to cause a click in the operator's receiver notifying her that the line is busy. In such case she will so advise subscriber A and by withdrawing the answering plug, restore switch C as hereafter described. If, however, the tested line be idle, contact 83 will be of the potential of ground preventing operation of relay 68; no click results from the test and the operator inserts the calling plug in the jack of line F. Current then flows from battery B² through relay 66, levers 72-78, contact 81-89, relay 87 to ground, energizing both relays and putting a busy potential on contact 83. Relay 87 attracts its armatures and the operator depresses levers 77 and 78 causing the projection of ringing current from generator 79 over the called line through condenser and call bell returning through lever 78, through battery B² to ground. The operator then restores the ringing key levers. Signal 88 is at this time displayed, but as soon as the called subscriber removes his receiver, circuit is closed from ground through relay 65, armature 67, (attracted when lever 78 was restored) through levers 71-77, contact 81-84, attracted armature of relay 87, through transmitter, receiver and hook lever at the substation, returning through the lower attracted armature of relay 87, contact 89-81 to battery through relay 66. Relay 65 therefore attracts its armature to open circuit through lamp 88 whose going out notifies the operator that the call has been answered. Subscribers A and F are now in conversation, the talking circuit being traced by the heavily marked conductors, talking current being supplied to the transmitter of subscriber A through the windings of relays 63 and 62 and to the transmitter of subscriber F, through relays 65 and 66.

When at the conclusion of conversation subscribers A and F replace their receivers, the shifting of the respective hook levers open the circuits of relays 62 and 65, which are deenergized, allowing their armatures to fall back closing circuits through lamps 64 and 88. The operator in response to the signals withdraws the calling plug H from the spring jack of the line of F which restores the line circuit and the calling end of the cord-circuit to normal. She also withdraws the answering plug G from the spring jack of the trunk line. The openings of contacts 60-54 and 61-52 cause relays 46 and 3 to release their armatures, the relay 46 being so adjusted as to allow relay 3 to deenergize and close circuit through magnet RM before normal contact of said relay 46 is again closed. Relay 34 is rendered sluggish in the release of its armature, which may be effected for instance by a copper shell about its core as shown. Armature 5 of relay 3 therefore engages its normal contact before armature 36 of relay 34 leaves its front contact, and circuit is closed from ground through retracted armature 5, contact 20-21, armature 36 and 125 its front contact, shifted off-normal switch, spring ON⁴, release magnet RM to battery. Magnet RM attracts its armatures locking itself from grounded armature spring 44, spring ON⁴ to battery, maintaining energized 130

until the switch reaches normal, when spring ON¹ and the other off-normal springs are restored to normal. Armatures 44-43 also close circuit from ground through relay 38 to battery B holding said relay energized during the release. The attracted right armature of magnet RM closes circuit from ground at the shifted off-normal spring ON² through relay 22 to battery, in order that relay 22 be energized and wipers 15 and 17 hence be on open circuit during the release. When the switch wipers are restored to normal, the off-normal springs are shifted back to the positions shown, ON¹ removing ground from contact 13, rendering the switch C selectable by the master-switch, ON² and ON³ open circuits to ground from battery through relay 22 causing its deenergization, the armatures of relay 34 being at this time retracted; the shifting of ON² also deenergizes relay 29, while spring ON¹ deenergizes magnet RM and its armatures 44 and 43 are retracted to open circuit through relay 38, and the selective switch C is at normal.

Let it be assumed that subscriber F desires his line connected with that of subscriber A. He removes his receiver, closing circuit from battery B², through relay 85, lower armature of relay 87, through hook-lever 1, receiver and transmitter at the substation, returning to ground over the upper armature of relay 87; relay 85 is energized to display signal 86, and the operator responds by inserting the answering plug G into the answering jack of the line, closing contacts 59-84, 60-89 and 61-83. Current then flows from battery B², through relay 63, contact 60-89, through cut off relay 87 to ground, energizing relays 63 and 87, the attracted armature of the latter extending the circuits of the line F to the spring jack contacts. Relay 62 is thereupon energized by current flowing from ground, through contact 59-84, over the line of F, returning through the attracted lower armature of relay 87, contact 89-60, relay 63 to battery. The energization of relay 62 causes it to attract its armature to prevent the display of supervisory signal 64. The operator now throws over levers 69 and 70 of her listening key and ascertains the number of the subscriber wanted (assumed to be A). She thereupon tests the multiple springjacks shown at D of the trunk lines assigned to the group of subscribers among which A is included. The test contacts 51 of busy trunks will be connected to battery B' by armature 48, as before described, or to battery B² at a cord circuit, if connection has already been made to a multiple of the spring-jack tested. In such cases, test relay 68 will be operated in a manner similar to that before described. As soon, however, as the operator tests a springjack of an idle trunk, now as-

sumed to be that shown at C, its test contact 51 will be on open circuit and test relay 68 fails to operate. The operator thereupon inserts the calling plug H into the springjack of the tested trunk, closing contacts 80-53, 70 81-54, the sleeve 82 crossing contacts 51 and 52. The closing of contact 82-51 connects battery B² to the test contacts of the trunk, rendering it busy. The closing of contact 82-52 completes circuit from battery B² through relay 46 to ground, operating the said relay, which attracts its armature to connect contact spring 54 to line limb L', cutting off relay 47. The operator now throws over levers 71 and 72 to connect her calling device 74, common to the position, with contacts 80 and 81 of the calling plug. Lever 72 when shifted in either direction closes its circuit to the opposed contact before it leaves the contact from which it is being shifted, and this is also true of lever 78 of the ringing key. This arrangement is to maintain a connection of battery B² to contact 81 of the calling plug so that relays 34 and 3 cannot become deenergized while the levers are being shifted, after they are once operated as hereafter described. It should be noted that the operator has, by testing the trunk jacks of a particular group of trunks and connecting with an idle one, 95 already selected an idle trunk leading to a limited group of subscribers' lines, among which that of the called-for subscriber is included. She now turns dial 74 in the direction indicated by the arrow until a number of teeth corresponding to the number of subscriber A in the group, plus one, have passed to the right of spring 75. In the meantime, the tooth shown in Fig. 2 at the right of spring 76 will have passed over the 100 top thereof so that, with the return of the dial to normal, it will momentarily open contact 76. The operator now releases dial 74 and it is turned by its associated spring in the opposite direction, its teeth causing 105 spring 75 to make and break contact with its associated spring a number of times, corresponding to the number of teeth passed to the right of spring 75. The first impulse thus transmitted flows from battery B², 110 through spring 75, levers 71 and 77, contact 80-53, over limb L of the trunk circuit, through back contact of armature 35 and said armature, through relay 37 to ground, energizing the said relay. The said relay there- 115 upon attracts its armatures, armature 37^a completing a circuit from ground, through its alternate contact, relay 29 to battery, which relay 29, by attracting armature 33, disconnects magnet M from the interrupter 120 I and shifts the connection of said magnet's winding to ground at the alternate contact of said armature 33, whereupon current flows from battery B, through the already attracted armature 37^a of relay 37, magnet 125 33 and back to ground. The connection of the 130

M, armature 33 to ground, operating magnet M, which moves wipers 15-17-19-21 a step. With this first step of the wipers, the off-normal switch springs are shifted, a locking circuit being completed for relay 29 from shifted spring O.N², while a circuit is completed from ground at the left, armature of relay 34, its back contact, through shifted off-normal spring O.N², attracted armature 31, relay 22 to battery, operating relay 22. Armatures 23 and 28 disconnect wipers 15 and 17 from battery and ground respectively; armature 26 completes circuit through relay 9, opening the starting conductor of the master-switch K; while armature 27 completes circuit from ground through relay 38, over limb L' of the trunk circuit to battery at the cord circuit, in order that relay 38 may be energized to disconnect the winding of test relay 39 from armature 28 before wiper 17 is brought to engage a contact forming a terminal of a line. With this first step of the switch, off-normal switch spring O.N' is shifted to operate relay 7 to cause wipers 10 and 11 to move on to engage and rest upon contacts, terminals of an idle switch C. The provision of a grounded contact, engaged by wiper 19 on its first step, is for the purpose of insuring time for the operation of relay 22 to disconnect the line wipers, and for the operation of relay 38 to disconnect the test relay 39 when the switch is used as a connector, before the line wipers engage the terminals of the first line. Said contact is grounded to cause the switch to pass over it when operating as a line selector. The succeeding impulses, transmitted by calling device 74 in its return to normal, pass through relay 37, which attracts and retracts its armatures, armature 37 causing a corresponding number of actuations of magnet M, which steps wipers 15-17-19-21 around to engage the contacts of the lines of the group—the last impulse of course placing them in engagement with contacts 14-16-18-20 of the line wanted. Immediately following the transmission of the last impulse, the tooth of calling device 74 opens contact 76 for a moment and then allows it to close. The opening of the said contact disconnects battery from lever 72, contact 81 and spring 54, causing momentary deenergization of relay 38 which was held energized during the transmission of the selecting impulses. The armature of the said relay is retracted, and the windings of polarized relay 39 are thereby momentarily connected to attracted armature 28 and to line wiper 17. Let it be assumed first that the called line is an idle line. In such case, the contact 16 engaged by wiper 17 will be at the same potential as ground, and current will flow from the intermediate tap of battery B, through test relay 39, retracted armature of relay 38, armature 28, contact 17-16, through relay 3 to ground. This current is in a direction to tilt the armature of polarized relay 39 to the right, which closes circuit from ground through the armature, to contact 41, through relay 42 to battery; the said relay 42 attracts its armature to open circuit through relay 22, whose armatures fall back. Relay 42 is preferably rendered slow to release its armature after it is once attracted, as for instance by a copper shell about its core, so that contact 76 will be closed and a circuit completed from battery B² through said contact, levers 72 and 78, contact 81-54, relay 34, retracted armature of relay 22, contact 17-16, cut-off relay 3 to ground, before relay 42 releases its armature. Hence relay 34 is operated and, by the attraction of its left-hand armature to disengage its normal contact, prevents relay 22 from again becoming energized when relay 42 releases its armature. Relays 34 and 3 are now both energized; armature 36 closed its contact in the circuit of release magnet RM extending to wiper 21, while armature 5 of relay 3 opened contact in the same circuit. Armature 35 of relay 34 opens the circuit of relay 37 to prevent its being again operated when, as hereafter described, the called subscriber establishes a flow of current over his line limbs. The operator now restores levers 71-72 and depresses her listening key levers 69 and 70 and, inasmuch as off-normal switch spring O.N' is shifted, disengaging its contact, she hears no signal from the interrupter I'. Thus, knowing that the called line is idle, she depresses levers 77 and 78 of her ringing key, projecting current from ringing generator 79 through lever 77, contact 80-53, over limb L of the trunk circuit, armature 23, contact 15-14, attracted upper armature of relay 3, line limb L², through the condenser, bell and hook-lever at the substation, returning over limb L², lower attracted armature of relay 3 to ground through relay 3, the current also returning over the talking conductor illustrated by the heavy line, through lever 78 and battery B² to ground. The operator then releases levers 77 and 78 which return to normal, 78 in its return keeping battery continually on contact 81 as before described, and relay 66 is connected in circuit with relays 34 and 3, said relay 66 attracting its armature and causing the display of signal lamp 88, which remains displayed until the called subscriber, removing his receiver in response to the signal, completes a circuit from ground through relay 65, attracted armature 67, levers 71 and 77, contact 80-53, armature 23, contact 15-14, over limb L², through transmitter, receiver and hook-lever at the substation, returning through contact 16-17, armature 125 130

28, relay 34, contact 54-81, relay 66 to battery, which flow energizes relay 65 and causes it to attract its armature to put out the lamp 88, notifying the operator that the subscriber has answered. Subscribers A and F are now in conversation, the talking circuit being traced by the heavily marked conductors and battery being supplied to the line of subscriber F, through the windings 10 of relays 62 and 63, and to the line of A through the windings of relays 65 and 66. When the subscribers have finished their conversation, they replace their receivers, causing the display of the two signal lamps 15 64 and 88, whereupon the operator withdraws the plugs of the cord circuit from the springjack, restoring the line circuit of F to normal and also restoring switch C to normal in a manner similar to that hereinbefore described.

Let it now be assumed that a selector switch has already connected to the line of A at the time relay 38 was deenergized to connect the test relay 39 with wiper 17. In such case, current will be flowing to ground through relay 3 from battery B', through relay 47, or from battery B' at the cord circuit if connection exists. Owing to the resistance of relay 3 and the other instrumentalities in the circuit, there will then be a potential at contact 16 of the line of A already engaged by another switch C and its multiples, now engaged by the switch making the test, greater than the potential 30 at the intermediate tap of battery B. Under these circumstances, a flow of current will take place, when relay 38 is deenergized, from contact 16, through wiper 17, attracted armature 28, winding of polarized relay 39, to the intermediate tap of battery B and to ground. This current flow, being in the reverse direction from that occurring when the called line was idle, tilts the armature of relay 39 to the left to 35 engage contact 40, whereupon current flows from the grounded armature, through contact 40, shifted off-normal switch spring O.N⁴, release magnet RM to battery B. Magnet RM thereupon locks itself as before described, continuing locked until the switch reaches normal. Its energization causes magnets 22 and 38 to be energized as before described; and when the switch reaches 40 normal, all apparatus is restored as before described. The operator, before throwing over her ringing-key levers, depresses her listening-key levers as before described and then receives from interrupter I' the busy signal, which passes through the now closed off-normal switch contact O.N⁵, its associated condenser, over limb L' of the trunk circuit, contact 54-81, through relay 66 to battery, charging and discharging the condenser in the sleeve strand of the cord, 45 and causing the customary buzz in the op-

erator's receiver. The signal will also be transmitted to the calling subscriber and the operator now restores her listening-key and withdraws the plugs without operating her ringing-key. The relay 37 may be so arranged as not to be responsive to the alternating current generator, used for ringing, sufficiently to fully attract its armature, in which case it will not be necessary for the operator to listen in before operating her ringing-key, as the calling subscriber will (on receiving the busy signal from interrupter I', if the called line be busy) replace his receiver to cause the display of the supervisory signal which will indicate to the operator that she should take down the connection.

The operations taking place when a subscriber, belonging to a group such as that to which A belongs, is to be connected to another subscriber of the same group or another group, will be understood from the description already given and a detailed description, which would consist merely of a repetition of one-half of the operations performed in putting through the connection already described, will not be given.

I show at O.R what may be termed an "over-run switch," its contact being normally open as shown. When the switch C has been in any way operated so far that its wipers pass beyond the last contacts contained in their banks, the contact of switch O.R is automatically closed to complete circuit through the release magnet RM when the switch will be restored to normal, de-energizing relay 9 to render master-switch K effective under control of calling subscribers.

It will be understood that the batteries shown at B' and B² may be a single exchange source of current, while that shown at B, supplying current to switches at a distance from the exchange, may preferably be a separate battery.

Referring to the mechanical drawings in Figs. 3 and 4 respectively, top and side views of the master switch, the terminals 10 and 11 shown at K in Fig. 1 are preferably common strips, as indicated in Figs. 3 and 4, 113 extending around under their respective sets of contacts 12 and 13, the wipers 10^a and 11^a having in themselves no circuit connections, but being arranged, when moved, to merely cross the common strips 10 and 11 to successive contacts 12 and 13 respectively. The contacts and common strips are arranged in a curved bank as shown, the wipers 10^a and 11^a being fastened to a suitably supported rotary shaft 92 to which is also fastened the circular rack 90, adapted to be engaged by the armature-driven pawl of magnet 8, and to be turned by successive thrusts of said pawl to move the shaft and wipers 10^a and 11^a one step for each thrust. 130

The parts of wipers 10^a and 11^a are disposed at such angles that one contact 11 and one contact 12 are always engaged by them. The movement of the wipers being always in the same direction, no restoring mechanism is required. The circuit-breaker for magnet 8 includes spring 91 and its contact, said spring being actuated to free its contact and open the magnet's circuit, by an associated arm fastened to the armature.

A preferred form of mechanism for use in connection with the circuit shown at C in Fig. 1 is shown in Figs. 5 and 6. Multiple line contact sets, comprising each contacts 14, 16, 18 and 20, are shown for fifty lines, disposed in two curved rows of twenty-five contact sets each, the contact sets of the first twenty-five lines of the fifty being superposed upon those of the last twenty-five lines, the permanently grounded contact 93 of Fig. 1 being shown at the left of the first contacts 14, 16, etc., in Fig. 5. The curved rows of contacts are rigidly fastened to main frame 102, and two sets of wipers 15, 17, 19 and 21 (those having the same numbers being connected together) are provided at the axis of curvature fastened to the rotary shaft 99, to which is also fastened one end of restoring spring 101 against whose tension the wipers and shaft 99 are turned. The two sets of wipers are set at such angle that when the set, whose wiper 15 is shown adjacent to contact 93, has been brought around so that it is about to leave its bank of contacts 14, 16, etc., the other set of wipers will be in a position such as to be about to engage the first contact set of its bank. The circular rack 96 is fastened to shaft 99 and is turned, carrying the shaft 40 and wipers around, by armature-driven pawl 94 of magnet M, moving the wipers a step for each thrust of said pawl. Retaining pawl 95 is held by its spring against rack 96 to prevent back movement during operation of the switch. With the first thrust of pawl 94, the stud 98, mounted on rack 96, releases off-normal switch spring ON^b which by its tension moves to disengage its contact, and also moves out of supporting relation with stud 104, whereon springs ON', ON'', ON''' and ON^c move to engage their respective contacts. If the switch operates so far that the wipers pass beyond the last contact set of the lower bank, stud 97 will engage over-run switch spring OR to cause it to engage its contact to operate the release magnet RM and restore the switch.

For restoring the switch mechanism to normal, the release magnet RM has, in addition to the ordinary armature spring combination indicated in full in Fig. 1, an armature extending over a rearwardly extending portion of pawl 95, rotatably mounted upon stud 103. When RM is energized, its

armature rotates pawl 95 to free rack 96, and the spring 101 (Fig. 6) is effective to rotate the shaft, carrying the rack and wipers, back to normal, stud 98 then engaging spring ON^b and shifting it back, whereby all the off-normal springs are restored. The arm 105, fastened to rack 96, normally engaging stud 103, moves away from the stud when the switch is operated; and on the restoration of the switch, serves, by again engaging stud 103, to stop the shaft, rack and wipers as soon as they reach normal.

I claim as my invention:

1. A telephone system including telephone circuits, link-circuits for interconnecting said telephone circuits, electrically actuated step by step selective switches therefor and for common use of said telephone circuits, and means for employing said switches interchangeably to connect with calling or called telephone circuits.

2. A telephone system including a telephone circuit, an electrically actuated step by step selective switch, a second telephone circuit, stations for said circuits, mechanism controlled at the station of the first circuit to automatically connect said switch with said first circuit when a calling circuit, and mechanism at the station of the second circuit for automatically controlling said switch to connect it with said first circuit as a called circuit.

3. A telephone system including a telephone line, an electrically actuated step by step selective switch adapted on initiation of a call at the station of said line to automatically select and connect with said line, a second telephone line and circuits controlled thereover for changing the mechanism of said switch to render it operable, responsive to currents over said second line, to select and connect with said first line as a called line.

4. A telephone system including a telephone line, multiple contacts for said line, electrically actuated step by step selective switches, and means for operating said switches for connecting to said contacts to extend the circuit of said line as either a calling or a called line.

5. A telephone system including telephone lines, link circuits for use in connecting said lines, and electrically actuated step by step switching mechanisms for said circuits for interchangeably connecting said circuits directly to said lines whether as calling or called lines.

6. A telephone system including a selective switch adapted to connect with either calling or called lines, a test relay for said switch adapted to test said lines as calling lines and a second test relay for said switch adapted to test said lines as called lines.

7. A telephone system including telephone lines, a link-circuit, a selective switch at one

- end of said link-circuit for connecting said link-circuit with said lines individually, and means for controlling the selective operation of said switch indifferently over said link-circuit and said lines, whereby said link-circuit is rendered capable of use for both incoming and outgoing calls of said lines. 65
8. A telephone system including a telephone line, electrically actuated step by step 10 selective switches at an exchange and means for selectively operating said switch indifferently for incoming and outgoing calls of said line. 70
9. A telephone system including a selective switch, a distributing device, a starting circuit controlled by said device for initiating an independent progressive movement of said switch multiple terminals pertaining to said switch, and means for altering the 15 normal electrical condition of said terminals upon initiation of said movement to render them busy. 75
10. In a telephone system, a link-circuit, multiple terminals therefor, a master-switch 20 terminal for said circuit, means for changing the normal electrical condition of said last-mentioned terminal, and means responsive to such changed condition to cause an alteration of the normal electrical condition 25 of said multiple terminals to render them busy. 80
11. A telephone system including a telephone line, a link circuit, multiple terminals at one end of said link circuit and a non- 30 multiple terminal at the other end of said link circuit, electro-magnetic means automatically controlled for advancing said non-multiple terminal into connection with said line when calling, means for altering the 35 normal electrical condition of said multiple terminals responsive to such automatic control, and means for also directively operating said non-multiple terminal for connecting to said line as a called line. 85
12. A telephone system including an electrically adjustable selective switch, circuits 40 capable of selection thereby, two controlling points for operating said switch, an operating magnet for said switch, a relay for controlling said magnet operable from one of 45 said points, a second relay for controlling said magnet operable from the other of said points, and means effective on operation of either relay to remove said magnet from control of the other relay. 90
13. A telephone system including electrically adjustable selective switching mechanism, a pair of relays each adapted for independently causing the operation of said 50 mechanism, and means for operating one of said relays to temporarily render the said other relay ineffective to control said mechanism. 95
14. A telephone system including a tele- 100
- phone line, a link-circuit, an electrically actuated step by step selective switch for said circuit, automatic means for operating said switch to select said line, and means for directively operating said switch to connect with said line. 105
15. A telephone system including a telephone line, an electrically actuated step by step selective switch, means controlled from the station of said line for causing said switch to automatically select said line, another telephone line, and means controlled at a station of said other line for directively operating said switch to connect with said first line. 110
16. A telephone system including a telephone line, contacts individual thereto, electromagnetically controlled step by step switching mechanism adapted to connect directly with said contacts, automatic means for adjusting said switching mechanism to connection with said line as a calling line, and electromagnetic means for directively adjusting said switching mechanism to connection with said line as a called line. 115
17. A telephone system including a group of telephone lines, an electrically actuated step by step selective switch at the exchange, automatic means for causing an independent progressive movement of said switch to cause it to pick out the calling line, and mechanism for directively operating said switch to select the called line. 120
18. A telephone system including a group of telephone lines having multiple terminal contacts at the exchange, electromagnetically 100 adjustable switching mechanism adapted to connect with said contacts, mechanism for automatically adjusting said switching mechanism to connect with any calling line of said group, said adjustment constituting the 105 first extension of a line as a calling line, and mechanism for causing said switch when idle to select a particular one of said lines, said selection constituting the final extension of a line as a calling line. 110
19. A telephone system including telephone lines and electromagnetically adjustable step by step selective switches for common use of said lines and adapted each to be indifferently employed as a line selector 115 to select the calling line or as a connector to select the called line. 125
20. The combination with a telephone line of an electrically controlled step by step selective switch adapted to automatically select 120 said line as a calling line, and mechanism for rendering said switch unavailable therefor and placing it under directive control. 130
21. A telephone system including a selective switch, multiple terminals adapted to be engaged thereby, means for causing an automatically controlled progressive movement of said switch engaging successive ter- 135

minals, and means for causing a directively controlled movement of said switch engaging successively said same terminals.

22. A telephone system including a selective switch, telephone lines having multiple contacts for engagement by said switch, a magnet for adjusting said switch, a relay for controlling said magnet sensitive to the electrical conditions of the contacts of said lines, a second relay for controlling said magnet insensitive to the electrical conditions of the contacts of said lines, means for transmitting a pre-determined number of current impulses to said second relay to cause said magnet to adjust said switch to engagement with contacts of a particular line.

23. A telephone system including a group of telephone lines, a plurality of selecting switches common to said lines each capable of automatic and directive operation in connecting with said lines, mechanism effective on initiation of a call over a line to cause one of said switches to automatically select the calling line, means for thereafter extending the circuit of said line past said selecting switch to another switch of said plurality, and mechanism for electrically adjusting said last-mentioned switch to connection with a particular called line of said group.

24. A telephone system including a group of telephone lines, a plurality of selecting switches common to said lines each adapted for automatic and directive operation in connecting with said lines, mechanism effective on initiation of a call over a line to automatically start one of said switches and cause it to select the calling line, means for isolating said selecting switch, link-circuits for extending the circuit of the calling line past said selecting switch to another switch of said plurality, mechanism for electrically adjusting said last-mentioned switch to select a particular called line of said group, and means for isolating said last-mentioned switch.

25. A telephone system including a plurality of groups of telephone lines, a plurality of selective switches for each of said groups of telephone lines, each switch adapted for automatic and directive operation to connect with the lines of its group, means controlled at the substation of a line to cause an idle switch of the plurality for the group to automatically select the line as a calling line, link-circuits for extending the circuit of the calling line past said switch to an idle one of said selecting switches for the same or any other group of lines, and means for electrically adjusting said last-mentioned switch to select a particular called line of the group to which it belongs.

26. A telephone system including a plurality of telephone lines, a calling line se-

lective switch common to said lines, means for starting said switch controllable at any calling substation of said telephone lines, a signal displayed when said switch is started, a circuit for extending the connection of said switch, and means controlled from said circuit for effacing said signal.

27. A telephone system including a plurality of telephone lines, a selective switch common to said lines, mechanism actuated on initiation of a call at a substation of a line for starting said switch, multiple test terminals for said switch, and means for altering the normal electrical character of said terminals to render them busy, effective when said switch is started from normal.

28. A telephone system including a group of telephone lines, a plurality of selective switches common to said lines each adapted for automatic and directive operation in establishing connections with said lines, means effective on initiation of a call over a line to cause one of said switches to automatically select the calling line, multiple terminals for said selective switch, means for changing the normal electrical condition of said terminals when said switch is in use to render them busy, link-circuits for extending the circuit of the calling line past said switch to another switch of said group, multiple terminals of said other switch, means for changing the normal electrical character of said terminals to render them busy, effective when said line is extended to said switch, and mechanism for electrically adjusting said last-mentioned switch to select a particular called line.

29. A telephone system including a group of telephone lines, selective switches for connecting with said lines, means effective on initiation of a call at a substation of a line to cause an idle one of said switches to automatically select the calling line, link-circuits for extending the circuit of the calling line beyond said switch to another idle one of said switches, and means for electrically adjusting said last-mentioned switch to connection with a particular called line.

30. A telephone system including a plurality of telephone lines, a less plurality of selective switches common to said lines, trunk circuits for said switches extending to the exchange, a signal for each trunk at the exchange, means effective on initiation of a call over a line to cause an idle one of said selective switches to automatically connect its trunk to said line and display its signal, operator's connecting means at said switchboard, apparatus included therein for extending the circuit of a trunk whose signal is displayed to an idle one of said switches, and mechanism controlled by the operator for electrically adjusting said last-mentioned switch to connect with a particular called line.

31. A telephone system including a plu-

1. A telephone system including a group of telephone lines, selective switches adapted to connect with said lines, means controlled at a substation for causing an idle one of said switches to automatically select the calling line, a telephone switchboard, and operator's connecting means therewith adapted to electrically cause adjustment of an idle one of said switches to connect with any one of said lines as a called line. 10
2. A telephone system including a group of telephone lines, selective switches common thereto, each adapted to be interchangeably employed for incoming or outgoing calls of said lines, a telephone switchboard, signals for said switches and multiple terminals therefor at said board, and operator's connective means for connecting a switch employed for an outgoing call to a switch employed for an incoming call. 15
3. A telephone system including a group of telephone lines, selective switches common thereto, each adapted to be interchangeably employed for incoming or outgoing calls of said lines, a telephone switchboard, signals for said switches and multiple terminals therefor at said board, operator's connective means for connecting a switch employed for an outgoing call to a switch employed for an incoming call, and means controlled by the operator for restoring said switches to normal. 20
4. A telephone system comprising a telephone line, a link-circuit, a switch having contacts for connecting said line and link-circuit, and means for establishing such connection automatically in response solely to a control exercised over said line as a calling line and directly in response to a control exercised over said link-circuit. 25
5. A telephone system including a line provided with a plurality of multiple terminals at the exchange, each terminal including a plurality of switch contacts, one serving as a test contact for the line as a called line, and another as a test contact for the line as a calling line, wipers movable over said contacts, and mechanism associated with said wipers and operable in different ways according to the condition of the encountered test contacts. 30
6. A telephone system including a subscriber's line, a terminal for said line at the exchange including a pair of test contacts, one serving to protect said line from intrusion when tested as a called line, the other to protect said line when tested as a calling line, a single unitary switch structure having movable test members for connection with said contacts respectively, and test devices connected with said switch sensitive to the electrical conditions of said test contacts. 35
7. A telephone system including a telephone line, a terminal therefor at the exchange including a pair of test contacts, a selective switch adapted for employment in extending the circuit of said line as either a calling or a called line, two test members for said switch adapted to be connected with said test contacts, test devices one for each said member, and means for employing the device of one member or the other according as the terminal is tested by said switch as the terminal of a called or calling line. 40
8. A telephone system including a selective switch, multiple terminals included in said switch, each terminal including a pair of test contacts, one test contact of each terminal being normally selectable and the other unselectable by said switch, means for rendering the normally selectable contact of a terminal unselectable by said switch, and means for rendering the normally unselectable contact of a terminal selectable by said switch. 45
9. A telephone system including a selective switch, multiple terminals included in said switch, each terminal including a pair of test contacts, one test contact of each terminal being normally selectable and the other unselectable by said switch, means for rendering the normally selectable contact of a terminal unselectable by said switch, means for rendering the normally unselectable contact of a terminal selectable by said switch, and means effective on selection made to render both said contacts unselectable. 50
10. A telephone system including a plurality of selective switches, terminals included in each said switch and multiplied from switch to switch, a pair of test contacts including in each said terminal, one being normally selectable and the other unselectable, test means for said switches sensitive to the electrical conditions of said normally selectable contacts, other test means for said switches sensitive to the electrical conditions of said normally unselectable contacts, means for rendering the normally unselectable contacts selectable, and means for rendering the normally selectable contacts unselectable. 55
11. A telephone system including a plurality of selective switches, terminals included in each said switch and multiplied from switch to switch, a pair of test contacts included in each said terminal, one being normally selectable and the other unselectable, test means for said switches sensitive to the electrical conditions of said normally selectable contacts, other test means for said switches sensitive to the electrical conditions of said normally unselectable contacts, means for rendering the normally unselectable contacts selectable, and means for rendering the normally selectable contacts unselectable. 60
12. A telephone system including a plurality of selective switches, terminals included in each said switch and multiplied from switch to switch, a pair of test contacts included in each said terminal, one being normally selectable and the other unselectable, test means for said switches sensitive to the electrical conditions of said normally selectable contacts, other test means for said switches sensitive to the electrical conditions of said normally unselectable contacts, means for rendering the normally unselectable contacts selectable, and means for rendering the normally selectable contacts unselectable, and means effective on selection made to render both said contacts unselectable. 65
13. A telephone system including a telephone line, a terminal therefor at the exchange including a pair of test contacts, a selective switch adapted for employment in extending the circuit of said line as either a calling or a called line, two test members for said switch adapted to be connected with said test contacts, test devices one for each said member, and means for employing the device of one member or the other according as the terminal is tested by said switch as the terminal of a called or calling line. 70
14. A telephone system including a selective switch, multiple terminals included in said switch, each terminal including a pair of test contacts, one test contact of each terminal being normally selectable and the other unselectable by said switch, means for rendering the normally selectable contact of a terminal unselectable by said switch, and means for rendering the normally unselectable contact of a terminal selectable by said switch. 75
15. A telephone system including a selective switch, multiple terminals included in said switch, each terminal including a pair of test contacts, one test contact of each terminal being normally selectable and the other unselectable by said switch, means for rendering the normally selectable contact of a terminal unselectable by said switch, means for rendering the normally unselectable contact of a terminal selectable by said switch, and means effective on selection made to render both said contacts unselectable. 80
16. A telephone system including a plurality of selective switches, terminals included in each said switch and multiplied from switch to switch, a pair of test contacts including in each said terminal, one being normally selectable and the other unselectable, test means for said switches sensitive to the electrical conditions of said normally selectable contacts, other test means for said switches sensitive to the electrical conditions of said normally unselectable contacts, means for rendering the normally unselectable contacts selectable, and means for rendering the normally selectable contacts unselectable. 85
17. A telephone system including a plurality of selective switches, terminals included in each said switch and multiplied from switch to switch, a pair of test contacts included in each said terminal, one being normally selectable and the other unselectable, test means for said switches sensitive to the electrical conditions of said normally selectable contacts, other test means for said switches sensitive to the electrical conditions of said normally unselectable contacts, means for rendering the normally unselectable contacts selectable, and means for rendering the normally selectable contacts unselectable. 90
18. A telephone system including a telephone line, a terminal therefor at the exchange including a pair of test contacts, a selective switch adapted for employment in extending the circuit of said line as either a calling or a called line, two test members for said switch adapted to be connected with said test contacts, test devices one for each said member, and means for employing the device of one member or the other according as the terminal is tested by said switch as the terminal of a called or calling line. 95
19. A telephone system including a selective switch, multiple terminals included in said switch, each terminal including a pair of test contacts, one test contact of each terminal being normally selectable and the other unselectable by said switch, means for rendering the normally selectable contact of a terminal unselectable by said switch, and means for rendering the normally unselectable contact of a terminal selectable by said switch. 100
20. A telephone system including a plurality of selective switches, terminals included in each said switch and multiplied from switch to switch, a pair of test contacts including in each said terminal, one being normally selectable and the other unselectable, test means for said switches sensitive to the electrical conditions of said normally selectable contacts, other test means for said switches sensitive to the electrical conditions of said normally unselectable contacts, means for rendering the normally unselectable contacts selectable, and means for rendering the normally selectable contacts unselectable. 105
21. A telephone system including a plurality of selective switches, terminals included in each said switch and multiplied from switch to switch, a pair of test contacts included in each said terminal, one being normally selectable and the other unselectable, test means for said switches sensitive to the electrical conditions of said normally selectable contacts, other test means for said switches sensitive to the electrical conditions of said normally unselectable contacts, means for rendering the normally unselectable contacts selectable, and means for rendering the normally selectable contacts unselectable. 110
22. A telephone system including a telephone line, a terminal therefor at the exchange including a pair of test contacts, a selective switch adapted for employment in extending the circuit of said line as either a calling or a called line, two test members for said switch adapted to be connected with said test contacts, test devices one for each said member, and means for employing the device of one member or the other according as the terminal is tested by said switch as the terminal of a called or calling line. 115
23. A telephone system including a selective switch, multiple terminals included in said switch, each terminal including a pair of test contacts, one test contact of each terminal being normally selectable and the other unselectable by said switch, means for rendering the normally selectable contact of a terminal unselectable by said switch, and means for rendering the normally unselectable contact of a terminal selectable by said switch. 120
24. A telephone system including a plurality of selective switches, terminals included in each said switch and multiplied from switch to switch, a pair of test contacts including in each said terminal, one being normally selectable and the other unselectable, test means for said switches sensitive to the electrical conditions of said normally selectable contacts, other test means for said switches sensitive to the electrical conditions of said normally unselectable contacts, means for rendering the normally unselectable contacts selectable, and means for rendering the normally selectable contacts unselectable. 125
25. A telephone system including a telephone line, a terminal therefor at the exchange including a pair of test contacts, a selective switch adapted for employment in extending the circuit of said line as either a calling or a called line, two test members for said switch adapted to be connected with said test contacts, test devices one for each said member, and means for employing the device of one member or the other according as the terminal is tested by said switch as the terminal of a called or calling line. 130

selection by a switch to render both test contacts of the selected terminal unselectable.

42. A telephone system including a selective switch, multiple terminals included therein, two test devices for said switch, and means for operating said switch to test said terminals by either of said devices according to the use in which said switch is employed.

43. The combination with a selective switch, including a multiple terminal having two test contacts individual to it and means for altering the electrical conditions of said contacts, of two test devices for said switch, one adapted to be placed in connection with each contact, and means for determining which of said devices shall be operative when a terminal is tested.

44. The combination with a selective switch, including a multiple terminal having two test contacts individual to it and means for altering the electrical conditions of said contacts, of two test devices for said switch, one adapted to be placed in connection with each contact, two circuits for initiating travel of said switch, and means for rendering the one or the other of said test devices operative when a terminal is tested according to the circuit employed.

45. In a telephone system, the combination with multiple contacts, of selective switches for selecting said contacts, a common starting conductor for initiating travel of said selective switches, a relay having a switch contact included in said starting conductor, and means for holding said relay energized as long as any selective switch is traveling to maintain open said starting conductor.

46. In a telephone system, the combination with multiple contacts, of selective switches for selecting said contacts, a common starting conductor for initiating travel of said selective switches, a relay having a switch contact included in said starting conductor, means for changing the electrical condition of said starting conductor to initiate travel of an idle switch, a switch contact included in said starting conductor, and a relay energized on starting of a switch to operate said contact to restore the normal condition of said conductor.

47. In a telephone system, the combination with multiple contacts, of selective switches for selecting said contacts, a common starting conductor for initiating travel of said selective switches, a relay having a switch contact included in said starting conductor, a switch contact included in said starting conductor, a relay energized on starting of a switch to operate said contact to restore the normal condition of said conductor, and means for holding said relay energized during the travel of the switch.

48. A telephone system including a telephone line, selective switches for selecting said line, a distributor switch for starting said selective switches, contacts of said selective switches at said distributor switch, means whereby said distributor switch normally engages a contact of an idle selective switch, a starting conductor for said distributor switch adapted to be interchangeably connected with said contacts, a relay for said distributor switch, a contact therefor connected with said conductor, and means effective on the starting and during the travel of a selective switch to hold energized said relay whereby said conductor is in its normal electrical condition.

49. In a telephone system, the combination with multiple contacts, of selective switches for selecting said contacts, a distributor switch for starting said selective switches, contacts of said selective switches at said distributor switch, means whereby said distributor switch normally engages a contact of an idle selective switch, a starting conductor for said distributor switch adapted to be interchangeably connected with said contacts, a relay for said distributor switch, a contact therefor connected with said conductor, and means effective on the starting and during the travel of a selective switch to hold energized said relay whereby said conductor is in its normal electrical condition.

50. A telephone system including a group of telephone lines, a plurality of selecting switches common to said lines each adapted for automatic and directive operation in connecting with said lines, mechanism effective on initiation of a call over a line to automatically start one of said switches and cause it to select the calling line, means for rendering busy said selecting switch, link-circuits for extending the circuit of the calling line past said selecting switch to another switch of said plurality, mechanism for electrically adjusting said last-mentioned switch to select a particular called line of said group, and means for rendering busy said last-mentioned switch.

51. A telephone system including a plurality of telephone lines, a selective switch common to said lines, a link-circuit extending from said switch to an operator's position, a call signal at said position, means for starting said switch, means for displaying said signal when said switch is started, and operator's means for extending the circuit of said link-circuit.

52. In a common battery telephone system, the combination with two groups of telephone lines and two groups of trunk lines, of a telephone line selective switch for each trunk line adapted for intermittent or step by step operation, a set of conductors for each group of telephone lines, means

- whereby the removal of the receiver of any telephone of either of said groups of telephone lines shall complete a circuit through the associated set of said conductors and 5 cause any one of the switches of the group of trunk lines associated with the group of telephone lines in which the operated telephone is included to operate and connect the telephone line of such removed receiver 10 to the trunk line associated with the operated switch, instrumentalities whereby the central operator may establish communication with the telephone line of the said removed receiver, and means whereby the central operator may effect the operation of any 15 switch of the other group of trunk lines and cause said switch to establish electrical connection with the line of the telephone with which communication is desired.
- 20 53. In a common battery telephone system, the combination with a trunk-line and a group of telephone lines, of a telephone line selecting switch for the trunk-line, adapted for intermittent or step-by-step operation, 25 suitable conductors, means whereby the removal of a telephone receiver shall complete a circuit through such conductors to cause said switch to connect the telephone line from which the receiver has been removed, 30 to the trunk-line, means whereby the central operator may also effect the operation of said switch and cause it to establish electrical connection with the line of the telephone with which communication is desired, 35 a busy-back signal for the central operator, and means for operating said signal if central attempts to establish communication with a busy line.
54. In a common battery telephone system, the combination with a group of telephone lines and a group of trunk lines, of a telephone line-selecting switch for each 40 trunk line susceptible of making electrical connection with any one of the group of telephone lines, a set of conductors for the group of telephone lines, means whereby the removal of a receiver of any one of the telephone lines shall complete a circuit through the said conductors to cause any 45 one of the said switches to operate and connect the telephone line of such removed receiver with the trunk line associated with the operated switch, and means whereby the central operator may effect the operation of 50 any other switch of said group through the trunk line associated therewith and cause said second switch to establish electrical communication between its respective trunk line and the telephone line of said group of lines, with which communication is desired.
55. In a common battery telephone system, the combination with a trunk-line and a group of telephone lines, of a telephone line-selecting switch for the trunk-line, suitable conductors, means whereby the removal 55 of a telephone receiver shall complete a circuit through such conductors to cause said switch to connect the telephone line from which the receiver has been removed to the trunk-line, and means whereby the central 60 operator may also effect the operation of said switch and cause it to establish electrical connection with the line of the telephone with which communication is desired.
56. In a common battery telephone system, 75 the combination with a trunk-line and a group of telephone lines, of a telephone line-selecting switch for the trunk-line, suitable conductors, means whereby the removal of a telephone receiver shall complete a circuit through such conductors to cause said switch to connect the telephone line from which the receiver has been removed to the trunk line, and means whereby a circuit may also be completed over the trunk line and 80 effect the operation of said switch and cause it to establish electrical connection with the line of the telephone with which communication is desired.
57. A group of telephone lines; a line 85 finder common to said group; a manual telephone switchboard; electrical connections between said finder and said switchboard; signaling apparatus at said switchboard controlled through said electrical connections; 90 and means whereby the line finder and the signaling apparatus may, through said electrical connections, become simultaneously active in response to a calling telephone line.
58. A group of telephone lines; a line 95 finder common to said group; a manual telephone switchboard; electrical connections between the finder and said switchboard; signaling apparatus at said switchboard controlled through said electrical connections; 100 means whereby the line finder and the signaling apparatus may, through said electrical connections, become simultaneously active in response to a calling telephone line; and means to restore apparatus to normal 105 position.
59. A telephone system including telephone circuits, link-circuits for interconnecting said telephone circuits, electrically actuated step-by-step selective switches therefor, and means for employing said switches interchangeably to connect with calling or called telephone circuits. 115
60. A telephone system including a telephone line and an electrically actuated step-by-step selective switch having contacts individual to said line, and means for automatically connecting to said contacts to extend the circuit of said line as either a calling or a called line. 120
61. A telephone system including telephone lines, a link-circuit for use in connecting said lines, and electrically actuated 125

step-by-step switching mechanism for said circuit for connecting said circuit directly to said lines whether as calling or called lines.

62. A telephone system including a telephone line, an electrically actuated step-by-step selective switch at an exchange, and means for selectively operating said switch indifferently for incoming and outgoing calls of said line.

13 63. A telephone system including a telephone line, a link circuit, an electrically actuated step-by-step selective switch for said circuit, means for operating said switch to automatically select said line, and means for 15 directively operating said switch to connect with said line.

64. A telephone system including a telephone line, contacts individual thereto, electromagnetically controlled step-by-step 20 switching mechanism adapted to connect directly with said contacts, mechanism for automatically adjusting said switching mechanism to connection with said line as a calling line, and electromagnetic means for di-

rectively adjusting said switching mechanism to connection with said line as a called line.

65. A telephone system including a group of telephone lines, an electrically actuated step-by-step selective switch at the exchange, 30 means for causing an independent progressive movement of said switch to cause it to pick out the calling line, and mechanism for directly operating said switch to select the called line.

66. A telephone system including telephone lines and electromagnetically adjustable step-by-step selective switches adapted each to be indifferently employed as a line selector to select the calling line or as a connector to select the called line.

In witness whereof, I hereunto subscribe my name this 24th day of November, 1906.

LERoy D. KELLOGG.
